UNITED STATES PATENT OFFICE.

ARTHUR B. KLEINHANS, OF EASTON, PENNSYLVANIA.

BUILDING CONSTRUCTION.

Application filed March 1, 1926. Serial No. 91,544.

The present invention relates to the construction of buildings and aims generally to improve the roof and its supporting means.

5 In the accompanying drawings I have illustrated as one embodiment of my invention, a greenhouse constructed in accordance therewith, wherein

Fig. 1 is a vertical cross-section of a part 10 of a greenhouse roof at the eaves, showing one form of astragal or sash bar and support therefor arranged according to my invention.

15 Figs. 2 and 3 are detail sectional views taken on the lines 2—2 and 3—3 respectively of Fig. 1, and

Fig. 4 is a perspective view of an astragal supporting lug conformable to my invention.

20 The construction illustrated in the drawings and to which my invention is adaptable preferably includes spaced metallic columns or posts 10, supporting rafters 11 which in turn support longitudinal roof supports or 25 stringers 12 of any suitable shape, as for instance angle bars, as is common in such construction. The stringers 12 support the spaced astragals or sash bars 13 which in turn support the sections or panels of coverings 14, illustrated herein as panes of glass. In constructing greenhouses according to 30 my invention I find it preferable to provide continuous astragals extending from the ridge pole or uppermost stringer, as 35 the case may be, to the sills 15, thereby avoiding the necessity of separate eaves plates, as is customary in such constructions.

According to the present invention the astragals or sash bars 13 are of channel 40 shape, being preferably of inverted U-shaped cross section, and are formed with laterally projecting side flanges 16 which support the panels or panes 14. These bars 13 preferably are formed of relatively heavy 45 gauge sheet metal, as for instance sheet steel, and are of sufficient strength to support the weight of the glass panes, yet, thin and resilient enough to permit flexing inwardly of their sides to accommodate elongation of 50 the glass panes due to increases in temperature. Any suitable means may be employed for holding the glass panes in place upon the astragals 13, for instance wire clips 17 as described in my prior Patent No. 1,000,819, 55 granted August 15, 1911.

My invention contemplates the provision of means for so supporting the astragals 13 upon the stringers 12 so as to permit of slight movements of the astragals relatively to the stringers to accommodate expansion 60 and contraction of the astragal and panes of glass due to temperature changes. In the illustrated embodiment of the invention, the astragals are supported upon the stringers 12 by means of supporting members or lugs 65 18, which are preferably formed with a neck portion extending within the channel of the astragal and pivotally secured thereto by means of a relatively loose pivotal connection, as for instance a pin 19 passing through 70 a slot 20 in the lug and alining holes in the side walls of the astragals. The pin 19 and slot 20 preferably are of such dimensions as to permit of movement of the astragals relatively to the structural framework 75 of the building in a direction extending longitudinally of the astragal, but to prevent movement of the astragals and panes in a direction transversely of their length. The supporting members or lugs 18 are pref- 80 erably formed with shoulders 21 for engagement with an edge of the angle iron or other stringer 12, and are preferably secured to the stringer 12 by a single fastening 22 as for instance a rivet or bolt. This construction 85 permits some yielding of the fastening means while maintaining a secure connection. Preferably the astragals 13 are supported at each stringer by lugs 18 thus secured thereto, and by similar lugs secured 90 to the lower sills 15, as is clearly shown in Fig. 1.

When the invention is applied to roof constructions, the supporting members or lugs 18 are preferably formed with a relatively long and narrow neck portion providing a clearance space on each side of the lug and between the lower edge of the flange 16 of the astragal 13 and the shoulder 23 of the lug. Thereby relative movement is 100 allowed for, and the free passage of drops of water which may collect upon the lower face of the astragal flange due to condensation or slight leaks in the roof is permitted. Thus my improved construction allows the 105 drops of water to flow down the under sides of the flanges 16 to the sides of the house; whereas if dripped at the lugs it would drip at points within the greenhouse and would soon kill plants which might happen to be 110

placed thereunder. Furthermore, this construction prevents the collection of drops of water upon the lugs 18 and stringer 12 which would quickly corrode and thus 5 weaken the structure.

The advantages of my invention are, its 10 simplicity, and its flexibility due to the means of supporting the astragal which permits of its movement longitudinally and sidewise to accommodate distortions due to 15 temperature. The channel shaped astragal of the type shown and described, adequately accommodates movements of the structure under most severe temperature conditions, 20 resulting in a minimum breakage of glass panes and preventing the loosening and cracking of putty which would otherwise cause leaks. Furthermore, the particular type of supporting lug shown facilitates the 25 erection and cheapens the cost of construction of structures of this type.

Although my invention is particularly adaptable to the construction of greenhouses or other glazed structures, it is also highly adaptable to the construction of other types of buildings and roofs, the outer surface of which may be covered with comparatively large panels or coverings. Hence, although I have referred to such 30 coverings in the claims as "covering panels" or "panes," for the sake of simplicity, it is to be understood that any suitable type of "rigid" or "semi-rigid" wall or roof covering is contemplated.

35 Obviously my invention is not restricted to the details herein shown and described.

What I claim is:

1. In a building structure, in combination with the structural framework including 40 stringers of covering panels or panes, astragals having a channel in its under side constructed of resilient material for supporting said panes and adapted to flex laterally to accommodate slight expansion of 45 the panes, means for supporting said astragals from the stringers to permit of slight movements thereof bodily in a longitudinal direction, said supporting means including lugs connecting said stringers and 50 astragals.

2. In a building structure, in combination with the structural framework including 55 stringers, of astragals loosely supported upon said stringers to permit of slight movement thereof bodily in a longitudinal direction, a plurality of covering panels or panes, said astragals being constructed of relatively 60 flexible sheet metal of channel form for supporting the panes and the sides of said astragals being capable of flexing inwardly to accommodate the expansion of the panes due to increase in temperature, the arrangement being such that said astragals and supported panes are capable of slight movements 65 as a unit upon the substructure.

3. In a building structure in combination with the structural framework including stringers, of covering panels or panes, channel shaped astragals constructed of resilient material adapted to support a plurality of panes, and accommodate slight expansion thereof, means for supporting said astragals from said stringers to permit of slight movements of said astragals bodily in a longitudinal direction thereof, said supporting means including lugs secured to said stringers, and means secured to said astragals having a relatively loose connection with said lugs. 70

4. In a building structure, in combination with the structural framework including stringers, of covering panels or panes, channel shaped astragals constructed of resilient material adapted to support a plurality of panes, means for supporting said astragals from said stringers to permit of slight movements of said astragals bodily in a longitudinal direction thereof due to temperature changes, said supporting means including lugs secured to said stringers, said lugs being shouldered for engagement over the edge of a stringer, and a single fastening means for fastening each lug to the supporting stringer. 80

5. In a roof construction, in combination with roof supporting members, a roof including covering elements, spacing members for spacing and supporting a plurality of covering elements, means for supporting said spacing members from said supporting members in spaced relation thereto, a portion of said supporting means being spaced from said spacing members whereby to provide for a free passage of drops of water collected upon the under side of said spacing members. 90

6. In a roof construction for greenhouses or other glazed structures, in combination with roof supporting stringers, of a roof including glass panes and channel astragals 100 for spacing and supporting rows of glass panes, means for supporting said astragals from said stringers and in spaced relation thereto, said supporting means including a relatively long neck portion adapted to extend within the channel and to support the astragal with the lower edges thereof spaced from the body of the said supporting means a distance sufficient to provide for the free passage of drops of water collected upon the under side of said astragal. 110

7. In a greenhouse or other glazed structure, means for supporting an astragal from roof supporting members or stringers, comprising a member having a body portion and an extending astragal engaging portion, the body portion of said supporting member being shouldered for engagement over an edge of the stringer, and being also formed with an opening for the reception of 120 130

a single fastening means for connecting said supporting member to said stringer.

8. In a greenhouse or other glazed construction means for supporting a channel shaped astragal from roof supporting members or stringers, comprising a lug having a body portion, and a neck portion adapted to extend into the channel of said astragal, the neck portion being formed with a slightly elongated opening adapted to loosely receive a securing element carried by said astragal, the body portion of said lug being shouldered for engagement over an edge of the stringer, and being also formed with an opening for the reception of a single fastening means, whereby said single fastening means provides a secure connection between said supporting member and said stringer.

9. In a greenhouse or like structure, a framework including spaced side columns and rafters connected thereto, stringers connecting said rafters and sills connecting said columns and positioned below the point of connection of the rafters and columns, a roof and wall covering comprising rows of glass panes, channel shaped metallic astragals extending across said stringers and downwardly to said sills for supporting said rows of glass panes, the side walls of said astragals being resilient to yield inwardly to accommodate expansion of the glass panes due to increases in temperature, and means for supporting said astragals in spaced relation to said stringers and sills to provide an unobstructed passage for water collected on the inner lower face of the astragal and permitting it to drain from the astragal at the point of connection of the astragal and sills.

10. In a greenhouse or like structure, a framework including spaced side columns and rafters connected thereto, stringers connecting said rafters and sills connecting said columns and positioned below the point of connection of the rafters and columns, a roof and wall covering comprising rows of glass panes, metallic astragals having a channel formed in the under side and laterally extending flanges for supporting the rows of glass panes, said astragals and supported panes extending across said stringers and downwardly to said sills thus providing a continuous glazed covering between said astragals, and means for supporting said astragals in spaced relation to said stringers and sills including a reduced neck portion extending within the channel of said astragal and connected thereto, thus leaving the lower faces of the lateral flanges of the astragals unobstructed, thereby to provide a free passage for water collected on the under side of the astragal and permitting it to drain from the lower end thereof.

11. In a roof structure for building and the like, in combination with a support or stringer, of an astragal having a chamber in the under side, a fastening element engaging said support and having a portion extending into said chamber, and means connecting said fastening element and astragal adapted to permit slight movement of the astragal in a direction longitudinally of its length but to prevent movement thereof relatively to the support in a transverse direction.

In testimony whereof, I have signed my name to this specification.

ARTHUR B. KLEINHANS.
